UNITED STATES PATENT OFFICE.

GUSTAF SIREN, OF DONORA, PENNSYLVANIA.

CONTROL MECHANISM FOR GAS-LAMPS.

1,318,184.

Specification of Letters Patent.

Patented Oct. 7, 1919.

Application filed June 13, 1917. Serial No. 174,510.

To all whom it may concern:

Be it known that I, GUSTAF SIREN, a citizen of the United States, residing at Donora, in the county of Washington and State of Pennsylvania, have invented certain new and useful Improvements in Control Mechanism for Gas-Lamps, of which the following is a specification.

This invention relates to improvements in control mechanism for gas lamps. One object is to provide manually operable means for controlling the supply of gas to the light to regulate the intensity of the light. A further object is to provide means for readily lighting the lights without inconvenience, gas control means being placed within easy reach regardless of the position of the gas lamp. A further object is to provide means for economizing gas in the operation of gas lamps. With the foregoing and other objects in view the invention consists in the combination and arrangement of parts to be hereinafter fully described, pointed out in the claim and illustrated in the drawing which forms a part of this specification.

In the accompanying drawing which is a side view of my improved control mechanism illustrating its application the numeral 1 denotes a gas lamp having the gas supply pipe 2 provided with a cut off valve 3 which is controlled by the stem 4 to which a pulley 5 is made fast. A chain 6 runs about the said pulley and has its ends secured to the ends of a pair of bell cranks 7, 8 fulcrumed upon a pin 9, the opposite ends of said bell cranks being engaged, respectively, by steel wires 10, 11 which are also secured, respectively, to other bell cranks 12, 13 fulcrumed upon a pin 14, said bell cranks last mentioned being connected by steel wires 15, 16, respectively, with a turnbuckle 17 and chain 18 which chain passes about a sheave 19, having a turning handle 20, and then connects with the said turnbuckle. The said sheave 19 is journaled in a bracket 21 suitably supported. A set screw 19^a carried by the said sheave 19 extends beyond the periphery of the same for engagement with one or the other of the stop pins 19^b carried by the bracket 21 and disposed in the path

of movement of the said set screw in such position as to limit the movement of the said sheave 19 to substantially one-quarter turn which is sufficient to regulate the flow of gas to the lamp. A small gas pipe 23 communicating with the pipe 2 supplies gas continually to the pilot light 24 which lights the lamp 1 the instant the gas is turned on in said lamp. 55

By means of the handle 20 of sheave 19 the bell cranks 12, 8 or 13, 7 may be moved upon their fulcrums to rotate the pulley 5 in one or the other direction to open or close the valve 3, partially or completely, to positively regulate the flow of gas through the pipe 2 to the lamp 1 to regulate the intensity of the light within said lamp. It is obvious that through the use of a device constructed along the lines of my present invention a very fine adjustment of the flow of gas to the lamp 1 is possible. 60 65 70

What is claimed is:—

A control mechanism for gas lamps including in combination with a gas valve, a pulley in operative connection with said valve, a flexible connection having its central portion engaged about said pulley, a pair of bell crank levers each having one arm thereof connected to one end of said flexible connection, a bracket, a second pair 75 80 of bell crank lever connections between the pairs of bell crank levers and the bracket, a sheave rotatable in said bracket, a handle for rotating said sheave, a stop on said sheave, a pair of stops on said bracket in 85 the path of the sheave stop for limiting the rotary movement thereof in both directions, and a second flexible connection having its central part engaged about said sheave and having its free ends connected to arms of 90 95 said last named pair of bell crank levers, one of said branches of said flexible connection including an adjusting device.

In testimony that I claim the foregoing as my own I have hereto affixed my signature in the presence of two subscribing witnesses.

GUSTAF SIREN.
